SHIRT OR LIKE GARMENT

Frank Di Iuglio, New Haven, Conn.

Application June 26, 1941, Serial No. 399,778

3 Claims. (Cl. 2—128)

This invention relates to shirts, and particularly to the construction of men's outer or dress shirts.

The invention specifically relates to the manufacture and construction of the center front portion of the shirt, in which part the buttonholes are formed. Men's shirts, as now manufactured, are provided with two meeting edges which overlap each other, the under edge portion having the buttons sewed thereon and the upper edge portion which overlaps and covers the under portion being provided with buttonholes through which the buttons project when the shirt is worn. These overlapping edges are usually reinforced or stiffened in some manner, particularly the outer edge portion in which the buttonholes are provided, and it is with this portion of the shirt that the present invention is particularly concerned.

It is desirable that this portion of the shirt be stronger than other parts as it is subject to considerable wear, in that the shirt must be buttoned and unbuttoned each time it is worn. It is, however, undesirable to make this part of the garment too thick and heavy, both on account of the material required and also on account of the fact that the garment would thereby be rendered somewhat cumbersome. I contemplate in the present invention the use of an additional strip or fold of material, which may be applied to the central portion of the front buttonhole strip to extend longitudinally thereof, which additional member will reinforce the buttonhole stay piece of the shirt, and at the same time will require little additional material and will add to the appearance of the garment.

One object of the invention is the provision of a shirt having a buttonhole strip or stay piece of improved construction.

A further object of the invention is the provision of an outer shirt having a center front portion or buttonhole stay piece provided with a longitudinally extending ornamental strip of two-ply thickness extending longitudinally of the shirt and disposed substantially centrally of the stay piece.

To these and other ends the invention consists in the novel features and combinations of parts to be hereinafter described and claimed.

In the accompanying drawing:

Fig. 1 is a front elevational view of a shirt embodying my improvements;

Fig. 2 is an enlarged fragmentary view of the front center or buttonhole stay piece of the shirt;

Fig. 3 is a sectional view on line 3—3 of Fig. 2;

Fig. 4 is a composite view showing the various elements employed in the construction of the stay piece shown in Fig. 3;

Fig. 5 is a view similar to Fig. 2 of a construction of modified form;

Fig. 6 is a sectional view on line 6—6 of Fig. 5;

Fig. 7 is a view similar to Fig. 4, showing the parts entering into the construction of the stay piece shown in Fig. 6; and

Fig. 8 is a view similar to Fig. 4, showing a further modification.

To illustrate a preferred embodiment of my invention I have shown a man's outer shirt, designated generally by the numeral 10, the shirt having a collar 11 and cuffs 12 of any preferred form. The shirt body comprises the front portions 13 and 14, the member 13 having provided thereon the buttonhole stay piece or center front portion designated by the numeral 15, which, as will be understood, overlaps, when worn, the edge of the body portion 14 in which are secured the buttons 16. When the edges of the shirt are overlapped, the buttons are passed through the buttonholes 17 formed in the portion 15.

The present application, as stated above, pertains particularly to the construction of the portion 15 of the shirt, in which the buttonholes are formed. It is more or less usual to provide along this portion of the shirt, extending downwardly from the collar as far as it is desired to button the same, a reinforced or stiffened portion in which the buttonholes are formed. This reinforced portion is shown more particularly in Figs. 2 and 3, and indicated by the reference character 18. From these figures it will be seen that a piece of material, usually of the same material as the body 13 of the shirt, may be folded so as to form a two-ply member which is secured by the rows of stitching 19 to the part 13 of the shirt front, the edge of which is folded over, as shown at 13^a, so as to present a finished appearance. If desired, the strip of material 18 may be folded about a strip of stiffening material

20 so as to further stiffen the front portion of the garment.

In order to further reinforce this portion of the garment, I provide an additional strip of material, as shown at 21, the longitudinal edges of which may be folded under, as shown in Figs. 3 and 4, so as to produce a strip of substantially two-ply thickness throughout its length. This two-ply strip 21 is then secured upon the outer surface of the usual buttonhole stay piece 18, and extends throughout the entire length of the

latter. It may be secured in place by a double row of stitching 22, one on each side of the central portion of the strip, so that the buttonholes 17 will lie therebetween. It will be seen that the strip 21 is substantially centered between the side edges of the strip 18 so as to provide a raised central rib upon the buttonhole stay piece, through which rib the buttonholes 17 are formed, as well as through the portion 18 and body 13 of the shirt. The superposed strip 21 may be of any desired material, such as, for example, the material of the body portion of the shirt, or it may be of a material of a contrasting color or pattern so as to serve an ornamental purpose as well as a functional purpose. As shown particularly in Fig. 3, this superposed strip is considerably narrower than the portion 18, and hence adds but little to the weight or bulk of this portion of the shirt, and requires little additional material.

In Figs. 5, 6 and 7 of the drawing I have shown a construction of somewhat modified form in which both members 18 and 21 are formed integrally of the same piece of material, and also formed integrally with the body 13 of the shirt. From these figures of the drawing it will be seen that the body portion 13 of the shirt is folded upon itself, as shown at 25, reversely folded, as shown at 26 and 27, and again folded, as shown at 28 and 29, and the free edge folded under, as shown at 30. Between the portion 25 and the portion 13, and the portions 29 and 30, the stiffening strip 20 may be employed. This forms substantially the same construction as that represented in Figs. 2, 3 and 4 of the drawing, except that the parts are all constructed integrally with the body 13 of the shirt. After the material has been folded as shown, the various plies may be secured in place by the rows of stitching 31 and 32, which, as shown in Fig. 5, extend upon each side of the buttonholes 17. In this instance it will be obvious, of course, that the strip of material 21^a, superposed upon the usual buttonhole stay piece, will be of the same material as the body of the shirt itself.

In the sectional view shown in Fig. 8 of the drawing, the construction is substantially like that shown in Figs. 6 and 7, except that the body of the shirt is separate from the other parts. That is, the buttonhole stay piece 32 and the superposed central strip 33 applied thereto are constructed of an integral piece of material, and are secured by stitching to the body 13 of the shirt, the edge of which may be folded over, as shown at 13^a.

The stiffening strip 20 may be of any suitable material, and preferably this strip will be of fusible material so that the buttonhole stay piece may be fused so as to present a starched appearance when the shirt is laundered. This will add to the attractive appearance of the garment, although the invention is also of advantage when the stiffening strip is merely of some heavy or relatively stiff material not capable of being fused.

While I have shown and described a preferred embodiment of my invention, it will be understood that it is not to be limited to all of the details shown, but is capable of modification and variation within the spirit of the invention and within the scope of the appended claims.

What I claim is:

1. A shirt front having a body portion with a front opening, a center front longitudinally extending buttonhole portion at one edge of said opening superposed on the body portion, and an additional strip superposed on said buttonhole portion and extending longitudinally thereof and having buttonholes extending therethrough, said additional strip comprising a plurality of plies of material whereby its outer surface is raised substantially above that of the buttonhole portion, and said additional strip being narrower than the buttonhole portion and applied thereto substantially centrally of the width thereof.

2. A shirt front having a body portion with a front opening, a center front buttonhole portion at one edge of said opening superposed on the body portion, and an additional strip, comprising a plurality of plies of material, superposed on said buttonhole portion and extending longitudinally thereof, said additional strip being narrower than the buttonhole portion and having buttonholes extending therethrough, and said center front buttonhole portion and additional strip being formed integrally of a single folded piece of material.

3. A shirt front having a body portion with a front opening, a center front buttonhole portion at one edge of said opening superposed on the body portion, and an additional plural ply strip superposed on said buttonhole portion and extending longitudinally thereof, said additional strip being narrower than the buttonhole portion and having buttonholes extending therethrough, and said center front portion and additional strip being formed integrally with each other and with the body portion of the shirt to which these parts are attached.

FRANK DI IUGLIO.
